UNITED STATES PATENT OFFICE.

FRANK LLOYD HOPWOOD, OF LONDON, ENGLAND, ASSIGNOR TO SUBMARINE SIGNAL COMPANY, OF PORTLAND, MAINE, A CORPORATION OF MAINE.

SOUND SCREEN.

Application filed July 7, 1920, Serial No. 394,542, and in Great Britain December 11, 1918.

(GRANTED UNDER THE PROVISIONS OF THE ACT OF MARCH 3, 1921, 41 STAT. L., 1313.)

This invention relates to underwater sound detecting apparatus of the single or double diaphragm directional hydrophone type.

5 The baffles or sound screen as hitherto used for directional purposes possess a disadvantage in that they are not capable of adjustment but when completed each baffle has to be used at a determined and invariable distance from the diaphragm of the hydrophone. While it is comparatively easy to construct a baffle which will be operative at a distance exceeding say two inches from the hydrophone diaphragm it 15 is difficult to make a number of such baffles which will work interchangeably or at a less distance. Further, out of those baffles which prove defective the majority are so because they destroy the bi-directional qualities of a 20 hydrophone before they endow it with unidirectional qualities.

According to this invention the baffle comprises a plate-like member in which is a closed chamber containing a measured and 25 variable quantity of liquid which does not completely fill the chamber. In addition to the liquid the chamber may contain a number of small loose bodies formed of suitable material and of similar size and shape 30 such as lead shot. The chamber is shallow and of its two main walls one is relatively thin while the other may be thin or relatively thick. One or more openings are formed through the thicker wall into the 35 chamber and means are provided for closing and sealing these openings as for example by means of screw plugs. The liquid used is preferably oil or water (either fresh or salt) and the desired quantity is inserted 40 into the chamber through one of the openings a second opening serving for the escape of air. When the liquid has been inserted the openings are closed and sealed. That portion of the chamber which is not 45 occupied by the liquid or by the loose bodies may contain air or gas or air may be exhausted therefrom.

A baffle thus constructed can be adjusted by varying the quantity of liquid within the 50 chamber so that the baffle will operate over a comparatively wide range of distances from the hydrophone diaphragm. Further, a baffle which may be defective in the manner above indicated may in some cases 55 be rendered efficient by modifying it in ac-

cordance with the present invention. The result of inserting liquid in the chamber is to diminish the distance between the baffle and the hydrophone at which the best working is obtained and to tend to correct what may 60 be termed overeffectiveness.

The invention may be put into practice in various ways but the accompanying drawings illustrate by way of example a convenient construction that may be adopted. 65

In these drawings:—

Figure 1 is an elevation of the improved baffle.

Figure 2 is a section on the line 2—2 of Figure 1.

Fig. 3 shows an arrangement in elevation whereby my invention may be put into practice, and

Fig. 4 is a sectional view showing details of the lower end of Fig. 3.

A plate A of suitable diameter and thickness constructed of xylonite or other similar non-resonant material has a circular recess B formed in it and of such depth that the thickness of the plate A' which forms one 80 wall of the recess is reduced considerably so as to constitute a relatively thin wall for the closed chamber. A xylonite disc C of substantial thickness is provided with a flange C' round its periphery and adjacent 85 to the flange a part C² of reduced diameter which is screw-threaded to engage the correspondingly screw-threaded cylindrical wall of the recess B in the baffle plate A. A washer D of suitable material such as 90 that known under the registered trade mark Dexine is disposed beneath the flange C' of the disc C and the face of the baffle plate A around the recess B and the disc C is then screwed home. The disc C constitutes a 95 relatively thick wall for the chamber B which is thus formed within the baffle plate A between the disc C and the opposite and relatively thin wall A' of the recess. In 100 this shallow circular chamber B are placed as many lead shot E as the chamber will contain the shot being similar in size and the diameter of each shot being slightly less than the distance between the two opposite flat walls of the chamber. Two holes C³ 105 are formed through the thick wall of the disc C each hole being screw-threaded and provided with a screw plug F which serves to close and seal the hole. Before these plugs are inserted a measured quantity of 110

liquid G for example water is poured into the chamber B the quantity being insufficient to completely fill the cavity. The amount of water employed may vary in accordance with requirements but as mentioned in no case must be the whole of the chamber be filled. When the liquid has been placed in the chamber the plugs F are inserted in the holes and the chamber is completely sealed up. In place of employing movable plugs the openings into the chamber may be permanently closed and sealed after the liquid has been inserted.

Though, as above described, the baffle is formed of xylonite it may be constructed of other suitable material for example ebonite, lead, glass, brass or other suitable metal. The disc C which constitutes the thicker wall of the chamber and serves to close in the one side of the recess B in the main plate A may be fixed in place otherwise than by screwing. For example this disc when formed of celluloid may be cemented in place. In place of water oil may be used or a viscous substance such as rubber solution.

With a baffle having a chamber of such dimensions as will contain 250 lead shot each of $\frac{1}{16}$ of an inch diameter it has been found that the best working distance is about $2\frac{3}{4}$ of an inch from the hydrophone diaphragm. When three cubic centimetres of water was placed in the chamber of this diaphragm this distance was reduced to $1\frac{1}{2}$ inches. If more water be added the distance will be still further reduced but if an excess of water is placed in the chamber the baffle may be rendered inoperative. If no shot are used a greater quantity of liquid is necessary in order to make the baffle work at a given distance from the hydrophone.

In Fig. 3 the baffle is shown at 1 arranged in relation to a microphone casing 2 which is supported at the lower end of a tube 3 through which are carried the microphone leads 4, the whole being properly supported in a gimbal frame 5 mounted on board ship, for example, in which it may turn. This frame forms no part of my invention and is well known in character and so is not further described.

The microphone casing 2 is illustrated in detail in Fig. 4 where 6 is a ring to which is screwed or otherwise attached a diaphragm 7 carrying a microphone and its casing 8. These parts may be of any ordinary

construction. The baffle plate A is provided with holes 9 through which pass bolts 10 which are screwed into the casing 6, the parts being held in proper relation by nuts 11, 12 being a ring preferably of brass for protecting the baffle from accidental injury.

What I claim as my invention and desire to secure by Letters Patent is:—

1. A baffle for use with underwater sound detecting means comprising a plate-like body having a tightly closed chamber containing a quantity of liquid, there being space in said chamber unfilled by said liquid. 65

2. A baffle for use with underwater sound detecting means comprising a plate-like body having a tightly closed chamber containing a plurality of small loose bodies of solid material and which are of similar size 75 and shape, said chamber also containing a quantity of liquid, there being space in said chamber unfilled by said liquid and said loose bodies.

3. A baffle for use with underwater sound 80 detecting means, comprising a plate having a recess therein, and a disk member located to close said recess to form a chamber in said baffle, said chamber having therein a plurality of loose bodies of similar size and 85 shape.

4. A baffle for use with underwater sound detecting means, comprising a plate having a recess therein, and a disk member located to close said recess to form a chamber in 90 said baffle, said chamber having therein a plurality of loose bodies of similar size and shape and being partially filled with a liquid.

5. A baffle for use with underwater sound 95 detecting means, comprising a plate having a recess therein, and a disk member located to close said recess to form a chamber in said baffle, one of the opposing walls of said chamber being relatively thin compared 100 with the other.

6. A baffle for use with underwater sound detecting means, comprising a plate-like body having a chamber therein, said chamber being partially filled with liquid, and 105 said plate-like body having means whereby said chamber may be filled with liquid and said liquid may be hermetically sealed therein.

In testimony whereof I have signed my 110 name to this specification.

FRANK LLOYD HOPWOOD.
